UNITED STATES PATENT OFFICE

109,938

DESIGN FOR A LUNCH BOX OR ANALOGOUS ARTICLE

John Ballantyne Lightfoot, Seymour, Conn., and Louis A. Trevisan, Bloomfield, N. J., assignors to American Can Company, New York, N. Y., a corporation of New Jersey

Application March 10, 1936, Serial No. 61,550

Term of patent 14 years

To the Commissioner of Patents:

Be it known that we, John Ballantyne Lightfoot, a citizen of the United States, residing at 125 Skokorat Street, Seymour, county of New Haven, and State of Connecticut, and Louis A. Trevisan, a citizen of the United States, residing at 65 First Avenue, Cor. No. 17th Street, Bloomfield, county of Essex, and State of New Jersey, have invented a new, original, and ornamental Design for a Lunch Box or Analogous Article, of which the following is a specification, reference being had to the accompanying drawing forming a part thereof.

Fig. 1 is a perspective view of a lunch box showing our new design.

Fig. 2 is a transverse fragmentary sectional view taken on line 2—2 of Fig. 1.

Fig. 3 is a transverse sectional view taken on line 3—3 of Fig. 1.

We claim:

The ornamental design for a lunch box or analogous article, as shown.

JOHN BALLANTYNE LIGHTFOOT.
LOUIS A. TREVISAN,
